United States Patent Office.

SAMUEL WINTER VALENTINE, OF BRISTOL, CONNECTICUT.

Design No. 4,937, dated May 23, 1871.

DESIGN FOR A PAPER BAG.

The Schedule referred to in these Letters Patent and making part of the same.

I, SAMUEL WINTER VALENTINE, of Bristol, in the county of Hartford and State of Connecticut, have invented or produced a new and original Design for a Paper Bag for Packing Handsaws, of which the following is a specification.

In the accompanying drawing is shown a side view of my design for paper bag, which, it will be observed, is a four-sided bag in the form of a trapezium.

The two longest side edges of the bag A are of about the same taper as an ordinary handsaw-blade, while the length of the bag is a little longer than the blade and handle combined of said saw.

The dotted lines indicate the proper place to fold the paper in closing the bag, when the line *a* indicates the large end of the closed bag, and the broken lines

b indicate the position of the edge of the paper at the mouth of the bag when so folded.

The design is one of utility, the bag being designed for packing handsaws, which will be found much more convenient and less expensive than ordinary wrapping-paper.

The maker's label, B, or trade-mark, may be printed or stamped upon one side of the bag.

I claim as my invention—

The design for a paper bag, as shown, and folded on the line *a*, substantially as described.

SAMUEL W. VALENTINE.
